UNITED STATES PATENT OFFICE.

MOSES GOLDING, OF TRENTON, NEW JERSEY.

MINING-PIT.

SPECIFICATION forming part of Letters Patent No. 321,714, dated July 7, 1885.

Application filed February 2, 1885. (No model.)

To all whom it may concern:

Be it known that I, MOSES GOLDING, a citizen of the United States and a resident of Trenton, Mercer county, New Jersey, have 5 invented a certain Improved Mining-Pit, of which the following is a specification.

My invention consists of an improved construction of mining pit as described and claimed hereinafter, more especially adapted 10 to the mining of kaolin.

In the accompanying drawings, Figure 1 is a vertical section illustrating a mode heretofore practiced of mining kaolin. Fig. 2 is a diagram illustrating an arrangement of my 15 improved pits. Fig. 3 is a plan view of part of my improved pit-lining; and Figs. 4, 5, and 6 are vertical sections showing the manner of building the pit.

Beds of kaolin are found at different depths 20 below the surface of the ground. Occasionally this mineral is so near the surface that it can be obtained by the ordinary process of quarrying, but most frequently it is at a considerable depth, say thirty to sixty feet below the 25 surface.

We will suppose that the irregular line *a* in the vertical section, Fig. 1, represents the upper surface of the bed *W* of kaolin, and that it is on an average of thirty feet below the 30 surface of the ground, indicated by the line *b*.

A plan heretofore practiced of mining is to dig a trench or pit of any desired length with sides at such inclination as to prevent the caving in of the soil. When the kaolin has been 35 reached, it may be mined to about the extent shown by the shaded portion *x* in Fig. 1, for the mineral is of such a cohesive character that it can be mined to a considerable extent 40 in the manner shown without caving in.

When a larger quantity of kaolin has to be mined, one or both the inclined sides of the pit must be cut away, in order to expose a more extended surface of the mineral. The inclined 45 dotted line *y*, for instance, shows how one of the sides of the pit or trench may be excavated in order to obtain the additional quantity of kaolin, indicated by dotted line *w*.

Another plan which has been resorted to is 50 that commonly adopted in mining other minerals—namely, the sinking of a comparatively small shaft, and on reaching the kaolin

making tunnels or headings therein communicating with the said shaft.

Both these methods, however, are tedious 55 and costly, and to meet this objection, and mine the kaolin more economically, I construct a pit preferably of circular form and with parallel sides, against which I construct a lining in sections, which are applied at intervals as the excavation is continued, as shown in Figs. 3, 4, 5, and 6. The lining is made of layers of timbers *M*, arranged in a circle, as appears in the plan view, Fig. 3, which shows part of one layer composed of timbers *M* and 60 part of an upper layer composed of timbers *M'*.

I have found that timbers each about four feet long, nine inches wide, and three inches thick will be available, these being arranged flatwise and abutting against each other, end 65 to end, and inclosing a circular space of any diameter desired, say twenty to forty feet.

The joints of the timbers are made on radial lines *m m*, and at one or more points in each layer are wedges *n n'* which serve a two-fold purpose. First, on driving the wedge *n* the timbers of the layer will be held in place, and, second, the wedges, entering the clay or 70 soil, serve to sustain the lining when it is undermined.

I first make a circular pit, *T*, Fig. 4, of such a depth that the bottom will afford a comparatively solid foundation, on which, after being properly leveled, I build a lining, *D*, composed of a number of the above-described 75 layers, driving the wedges as layer after layer is added to the structure, after which I continue the excavation of a pit to a depth which the character of the soil may suggest, the excavation being extended laterally beneath the 80 lining already built, as shown in Fig. 5. After this second excavation has been properly leveled I build thereon another series of the above-described layers until they reach the bottom layer of the first series; or, if the highest layer of the second series does not quite 85 reach the bottom of the first, and the space between them does not permit the introduction of another layer, I drive wedges between the two sets of layers. The excavation is again 90 proceeded with, as shown in Fig. 6, and a third set of layers added to the second, and these operations are continued until the kaolin 95 has been removed to an extent which the 100

character of the bed may suggest. After this I proceed to withdraw the wedges of the lowest layer, draw the latter into the pit, and hoist them therefrom, the filling of the pit being then commenced and continued as the withdrawal of the layers permits, and this removal of the lining and the introduction of the filling is proceeded with until the whole of the said lining has been removed, the timbers then being ready for use in making another excavation adjoining the first.

Referring again to the wedges, it should be understood that those of one layer are not directly above those of the other. The wedges appertaining to the layer of timbers M', for instance, may be at the points indicated by dotted lines, and this change in the position of the wedges in the different layers is adopted throughout the structure, so that the lining will have wedges projecting in every direction into the soil.

In the plan view, Fig. 2, is illustrated the plan which I prefer to adopt of sinking successive pits adjacent to each other—that is, after first refilling one pit, excavating another adjoining the filled pit.

The dotted circles *a b c d* represent excavations which have been sunk and the pits filled, while the plain circle *e* shows the position of a lined pit which is being formed for the removal of kaolin.

Although the practical application of my invention has been restricted to the mining of kaolin it may be employed in mining other minerals.

I claim as my invention—

The herein-described mining-pit having a supporting-lining consisting of a succession of circular layers of timber abutting against each other, end to end, and wedges holding the timbers and passing into the soil, substantially as described.

In testimony whereof I have signed my name to this specification in the presence of two subscribing witnesses.

MOSES GOLDING.
